UNITED STATES PATENT OFFICE.

DANA E. HARDING, OF MELROSE, MASSACHUSETTS, ASSIGNOR TO HARDING-WALCOTT COMPANY, OF EAST BOSTON, MASSACHUSETTS, A CORPORATION OF MASSACHUSETTS.

WEIGHTING MACHINE.

Application filed May 21, 1927. Serial No. 193,298.

My present invention relates to an improved weighting machine.

In my copending application, Serial No. 732,070 filed Aug. 14, 1924, I have described and claimed an improved form of weighting or grading machine for determining the relative weight or grade of leather. In such machine, the strip or sheet of leather or other material is fed by means of suitable devices under a plurality of parallelly arranged and independently rotatable and movable wheels or discs, which wheels or discs are connected through a system of levers to an indicating device. By means of the system of levers, the average weight or thickness of the hide or skin on that portion of the sheet material engaged by the measuring wheels or discs is measured, and such measurement is visually indicated on an appropriate indicating device. Where the sheet material, such as leather, has a glazed surface, no difficulty is experienced with the machine, either with regard to the accuracy of the measurements obtained thereby or with the quality of the product operated. When, however, an unglazed sheet of leather or other material, such as buckskin or suede, is passed through the machine for the purpose of measuring, it is found that the measuring wheels or discs, even though relatively light, show a tendency to compress the leather or other sheet material and there is, in many instances, well defined lines along the length of the leather or other material due to the compressing effect of the measuring wheels. This is objectionable and has, on extremely high-grade leather, for example, precluded the use of this machine.

In order to overcome this difficulty, I have devised the subject matter of the present invention, and in carrying out my invention I associate with the measuring machine and in combination with the measuring rolls, a rotating brush or brushes which act on the surface of the leather or other sheet material and erase or obliterate the visible effects of the measuring wheels.

The object of my invention, therefore, is an improved weighting machine.

In the accompanying drawings, illustrating the preferred embodiment of my invention,

Fig. 1 is a longitudinal section, and

Fig. 2 is a plan view on the line 2—2 of Fig. 1.

Referring to the drawings, 10 designates a base on which is mounted at the top end a platform 11. Rotatably mounted in the base is a shaft 12 on which are mounted at one end fast and loose pulleys 13 and 14 respectively. On the shaft 12 is a feed roll 15 which extends upwardly through a transverse slot 16 in the platform 11 to a point slightly above the upper surface of said top. Also, rotatably mounted in the base 10 and lying parallel to the shaft 12, is a second shaft 17 on which is secured a roll 18, this roll 18 also extending upward through a transverse slot 19 in the platform 11 to a point slightly above the upper surface of such platform. Secured to the shafts 12 and 17 and in alignment with each other are sprockets 20 and 21 respectively, and over these sprockets runs a sprocket chain 22 and by means of which power is transmitted from the shaft 12 to the shaft 17, such shafts rotating in the direction of the arrow shown in Fig. 1. Mounted above the platform 11 on suitable upward extensions of the base 10 is a cross bar 23, on the front end of which is secured downwardly extending brackets 24. These brackets at their lower end have secured a shaft 25, on which is rotatably mounted bell crank levers 26, having rotatably mounted thereon a feed roll 27 co-operating with the feed roll 15. Secured also to the bell crank levers 26 is an operating arm 28 associated with the operating mechanism of the indicating device. On the side of the bar 23 opposite the brackets 24 is secured a plurality of brackets 29, to each of which brackets is pivotally mounted one end of a rectangular framework 30, and in each of the frameworks 30 is rotatably mounted a measuring wheel 31, which measuring wheels 31 co-operate with the roll 18. The other end of these rectangular frames 30 are connected through suitable mechanisms, though not essential to the present invention, with the indicating mechanism of the machine. If a sheet of leather or other flexible material 32 is fed by the feed rolls 15 and 27 through the machine and into engagement with the roll 18 and the measuring wheels 31, the average thickness of the leather or other

sheet material will be measured and will be visually indicated on the indicating device associated with the machine. These measuring wheels 31, while relatively light, constitute with the rectangular frames 30 a sufficient weight so that they produce a certain ironing or compressing effect on the leather 32, and this ironing or compressing effect is particularly indispensable in leathers such as buckskin or suede or any rough or unfinished surface leather, and such markings tend to lower the quality of the leather from a selling point of view.

In order to overcome the objection last above noted, I have mounted beneath the platform 11, in bearings in the base 10 and at the rear of the measuring wheels 31, a shaft 35 which carries a roll 36 that extends through a transverse slot 37 in the platform 11 and to a point slightly above the upper surface of the platform. Also, I have rotatably mounted in suitable bearings in the upward extensions of the base 10 a shaft 38 parallel to the shaft 35, and both said shafts parallel to the shaft 17 and 12 and on the shaft 38 I mount a brush roll 39. The shaft 38 and, therefore, the brush roll 39 is driven in the same direction as the measuring wheels 31 but at a greater surface speed than such measuring wheels 31 by means of a train of gearing 40 extending between the shaft 17 and shaft 38. Suitable means is provided for varying the tension

between the surface of the brush roll 39 and the roll 36 and, therefore, the brushing effect of the brush roll 39 on the surface of the leather 32 may be made anything desired within reasonable limits. Accordingly, when a sheet of leather 32 is fed through the machine and between the measuring wheels 31 and the roll 18, the marks left by the measuring wheels 31 are brushed out or obliterated by the brushing effect of the brush roll 39.

By these means, all objections to the use of the measuring or weighting machine on all classes of leather is obviated.

Having thus described my invention, what I claim as new is:

In a weighting or grading machine for leather and the like, the combination of a feed roll, measuring wheels associated therewith, means for driving the feeding roll at a predetermined speed, a brushing roll for brushing out of the leather the marks impressed therein by the measuring wheels in the passage of the leather through the machine, and means connected to the feeding roll driving means for driving said brushing roll in the same direction as before at a greater speed than the speed of the feeding roll.

In testimony whereof, I have signed my name to this specification.

DANA E. HARDING.
